(57) **CLAIM**

The ornamental design for a mobile phone protection case, as shown and described.

DESCRIPTION

FIG. 1 is a front view of a mobile phone protection case showing my new design;

FIG. 2 is a rear view thereof;

FIG. 3 is a left side view thereof;

FIG. 4 is a right side view thereof;

FIG. 5 is a top plan view thereof;

FIG. 6 is a bottom view thereof;

FIG. 7 is a front, right-side, and bottom perspective view thereof; and,

FIG. 8 is a rear, left-side, and bottom perspective view thereof.

The broken lines immediately adjacent the shaded surfaces represent boundaries of the claimed design. All other broken lines depict environmental subject matter that forms no part of the claimed design. The broken lines and unshaded surfaces bounded by broken lines form no part of the claimed design.
